US0D1036438S

(12) **United States Design Patent** (10) **Patent No.:** **US D1,036,438 S**
(45) **Date of Patent:** **** Jul. 23, 2024**

(54) **HEAD-MOUNTED DISPLAY**

- (71) Applicant: **META PLATFORMS TECHNOLOGIES, LLC**, Menlo Park, CA (US)
- (72) Inventors: **Quintin Morris**, Seattle, WA (US); **Peter Wesley Bristol**, Seattle, WA (US)
- (73) Assignee: **META PLATFORMS TECHNOLOGIES, LLC**, Menlo Park, CA (US)

(**) Term: **15 Years**

(21) Appl. No.: **29/873,667**

(22) Filed: **Apr. 5, 2023**

Related U.S. Application Data

- (63) Continuation of application No. 29/866,289, filed on Sep. 7, 2022, now Pat. No. Des. 986,244, which is a continuation of application No. 29/811,933, filed on Oct. 18, 2021, now Pat. No. Des. 964,988.

(57) **CLAIM**

The ornamental design for a head-mounted display, as shown and described.

DESCRIPTION

FIG. 1 is a front perspective view of a head-mounted display showing our new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

The broken lines depict portions of the head-mounted display that form no part of the claimed design.

1 Claim, 7 Drawing Sheets
